APPARATUS FOR RECORDING THE DURATION OF A TRANSIENT EFFECT

Walther Richter, Whitefish Bay, and William H. Elliot, Shorewood, Wis., assignors to Cutler-Hammer, Inc., Milwaukee, Wis., a corporation of Delaware

Application October 7, 1943, Serial No. 505,274

6 Claims. (Cl. 234—1.5)

1

The invention relates to apparatus for recording the duration of a transient effect, and while not limited thereto is particularly applicable to an instrument for providing a permanent record of the duration of an arc obtaining between contacts in an electric circuit when said contacts are separated and thereby interrupt a current which flows in the circuit.

An object of the invention is to provide an instrument for recording the duration of an arc incident upon the closing or opening of a circuit carrying a current.

Another object of the invention is to provide an instrument of high accuracy for measuring and recording the duration of a transient phenomenon.

Another object is to provide an instrument for recording the duration of phenomena of great speed.

Another object is to provide an instrument of the aforementioned character capable of recording automatically the duration of several arcs occurring in rapid succession.

In the co-pending application Serial Number 445,393, filed June 1, 1942, which resulted in Patent Number 2,377,969, granted June 12, 1945, to Walther Richter, one of the applicants of the present application, and assigned to the same assignee as the present invention, a system is disclosed for determining the duration of a transient effect and particularly the duration of arcing in a circuit, but the system disclosed in said application is not capable of making a permanent record of the duration of arcing, nor is said system capable of recording separately the duration of several arcs which follow each other in rapid succession. The present system is an improvement of the system disclosed in the aforementioned application.

The accompanying drawing is a diagrammatic representation of a system embodying the invention. For the purpose of illustrating the operation of the system, the drawing shows an electromagnetic switch having an energizing winding 1^a, and a contact 1^b and it is intended to determine the arcing of the switch contacts upon closure of the same as will hereinafter be explained. The switch is connected to control a load 2. For this purpose power is supplied from the direct current lines L¹, L² through a manually operable switch 3, the current passing from line L¹, through an adjustable resistor 4, through the contacts 1^b, load 2, switch 3, to line L². The energizing coil 1^a has one terminal connected to the line L¹, while the other terminal is connected through a normally open contact 5, through the switch 3 to line L².

The measuring circuits are supplied with power from a direct current source through the bus bars 6, 7, 8 and 9, and for the purpose of illustration it

is assumed that the potential of the bus bar 6 is zero and that the bus bars 7, 8 and 9 are plus 90, plus 240 and plus 400 volts, respectively. The bus bar 6 is connected to line L¹. Connected to the common point of the contact fixed contact of the switch 1^b, and the resistor 4, is the cathode 10^a of an electron tube 10, which is also provided with an anode 10^b and a control grid 10^c. The control grid 10^c is connected in series with a resistor 11 and a biasing battery 12, or other source of direct current voltage, to the terminal of the switch 1^b which is nearest to the line L². The battery 12 has its positive pole arranged nearest to the grid 10^c. The cathode 13^a of an electron tube 13 is connected to the line L¹. The electron tube 13 is also provided with an anode 13^b, and a control grid 13^c. The control grid 13^c is connected to the common point of the resistor 4 and the contacts 1^b. The anodes 10^b and 13^b are connected together and in series with a variable resistor 14 having an adjustable contact 14^a, connected to the bus bar 8. A twin electron tube 15 is provided with a cathode 15^a cooperating with an anode 15^b and a cathode 15^c cooperating with an anode 15^d. The cathode 15^a and the anode 15^d are connected to the common points of the anodes 10^b, 13^b, and resistor 14, while the cathode 15^c is connected to the bus bar 7. The anode 15^b is connected to one terminal of normally closed manually operated push button 16.

The system further provides a pentode tube 17, having a cathode 17^a, an anode 17^b, a control grid 17^c, a screen grid 17^d, and a suppressor grid 17^e. The plate current of this tube is substantially constant over a wide range of plate voltages for constant screen grid voltage. The cathode 17^a is connected to the bus bar 7. The control grid 17^c is connected to the second terminal of the push button switch 16. The screen grid 17^d is connected to the movable contact 18^a of a resistor 18, which in turn is connected in series with the variable resistor 19 the resistors 18 and 19 bridging the bus bars 7 and 8. The resistor 19 is provided with a variable contact 19^a. The suppressor grid 17^e is connected to the bus bar 7. Resistors 20 and 21 are connected in series with each other between the bus bars 6 and 7, while the common terminal of the two resistors is connected through a resistor 22 to the second terminal of the push button switch 16. The anode 17^b is connected in series with a variable condenser 23 to the adjustable contact 19^a of resistor 19. The condenser 23 is paralleled by a circuit containing a milliammeter 24 and a normally closed contact 25. The common terminal of anode 17^b and condenser 23 is connected to the control grid of 26^c of an electron tube 26, which is also provided with a cathode 26^a, an anode 26^b, and a grid 26^d. The anode 26^b is connected to the bus bar 8, while the cathode 26^a is connected

through the resistor 21 to the bus bar 7. Thus the tube 26 and the resistor 27 form two adjacent branches of a Wheatstone bridge. The two other branches of the Wheatstone bridge comprise the resistors 29 and 30, which are connected in series with each other and between the bus bars 7 and 8. Across the common terminal of the tube 26 and resistor 27 and the common terminal of the resistors 29 and 30, respectively, is connected a microammeter 31 and a circuit paralleling the ammeter comprising the resistor 32 and the normally closed push button switch 33. The cathode 26^a is further connected through a normally open contact 34 to the grid 35^c of an electron tube 35 having a cathode 35^a and an anode 35^b. The cathode 35^a is connected to the bus bar 8 through a battery 43. A condenser 36 is connected between the cathode 35^a and the grid 35^c. The anode 35^b is connected through a resistor 37 to the energizing coil 38^a of a recording instrument 38 having a recording needle 38^b which makes a permanent record of its deflections on a ribbon or the like 38^c. A resistor 39 is connected between the common terminal of the resistor 37 and the coil 38^a, and the bus bar 8, while a bias battery 40 has its negative terminal connected to the free terminal of the coil 38^a and its positive terminal to the bus bar 8. The instrument 38 may be any suitable type of recording meter, preferably of the graphic type, wherein the magnetizing coil 38^a forms an armature which is rotatably supported in the air gap of a permanent magnet. A stylus or pen is fastened to the armature to rotate therewith as the armature is deflected in accordance with the current in the magnetizing coil. The pen makes contact with a chart which is moved by a clockwork and thus a diagram, showing the variation of the current for different positions of the chart and corresponding to different moments of time, is drawn on the chart in a well known manner. Thus a record of each operation of the system is obtained.

To make the operation of the system automatic it includes an electric motor 41, on the shaft of which is mounted a pinion 42 which meshes with a gear 43 having twice the diameter of the pinion 42. The gear 43 is mounted on a shaft 44, so that the motor and its shaft make two revolutions for each revolution of the shaft 44. Mounted on the shaft 44 is a cam 45 which opens and closes the switch 34 once during each revolution of the shaft 44, that is, during each second rotation of the motor 41. A second cam 46 mounted on the motor shaft opens and closes the contacts 5 once during every revolution of the motor, while a cam 47 opens and closes the contacts 25 upon each revolution of the motor 41.

The system as shown is arranged to record two succeeding cycles of operation of the switch 1 on different recorders. To make this possible the system is further provided with the normally open contact 134 which connects the cathode 26^a to the grid 135^c of an electron tube 135 having a cathode 135^a and an anode 135^b. The cathode 135^a is connected to the bus bar 8 through a battery 148. A condenser 136 is connected between the cathode 135^a and the grid 135^c. The anode 135^b is connected through a resistor 137 to the energizing coil 138^a of a recording instrument 138 having a recording needle 138^b which makes a permanent record of its deflection on a ribbon or the like 138^c. A resistor 139 is connected between the common terminal of the resistor 137 and the coil 138^a and the bus bar 9, while a bias

battery 140 has its negative terminal connected to the free terminal of the coil 138^a and its positive terminal to the bus bar 9. To operate the switch 134 the shaft 44 is provided with a cam 145 which is similar to the cam 45, but arranged to be displaced therefrom 180 degrees so that the switches 34 and 134 are operated alternately at alternate revolutions of the motor 41.

It will be apparent that the second recorder and the elements connected therewith, including the switch 134 and the cam 145, may be omitted. In this case the cam 45 could be placed directly on the shaft of the motor 41, whereupon the system would record a phenomenon for each rotation of the motor.

It will also be obvious that the motor may be geared to the shaft upon which the connections are mounted so as to record phenomena which are of longer duration than one revolution of the motor 41.

It will also be apparent that the number of recording instruments may be increased over that shown in the diagram. The necessary modification in this case is obvious.

Referring to the drawing it will be observed that on account of the rectifier action of the tube 15, current can only flow in the resistor 22 in a direction to increase the negative potential of the grid 17^c with respect to the cathode 17^a. The resistors 22, 20 and 21 are so proportioned that with no current flowing in resistor 22 a current of suitable value is flowing in tube 17. The cathode 15^a is connected to the resistor 14 which is the common load resistor of the tubes 10 and 13. The tube 10 is normally conducting but is rendered non-conducting when its grid 10^c is made sufficiently negative with respect to its cathode 10^a, that is, when there is a voltage drop across the contacts 1^b exceeding the voltage of the battery 12 by the necessary amount.

The battery 12 insures a small positive potential on the grid 10^c to compensate for a possible voltage drop of the switch contacts 1^b in the closed position, which drop might render the grid 10^c negative and stop current flow in the tube 16 when not desired.

The tube 13 is non-conducting if a sufficient voltage drop exists in the resistor 4. This takes place when switch 1 is closed and carries current or when it is open and an arc maintains current flow in the load circuit. The tube 10 responds to the voltage across the switch contacts 1^b. The time during which an arc exists between the contacts 1^b is therefore characterized by the simultaneous stoppage of current through the tubes 10 and 13. When either tube 10 or 13 carries current, the current flows through the resistors 14 and 22, the normally closed contacts of push button switch 16, and anode 15^b to cathode 15^a, through the respective tubes 10 or 13 to bus bar 6. The flow of current through the resistor 22 makes the grid 17^c sufficiently negative to stop the flow of charging current through the tube 17. With the switch 25 closed the charging current can be read on the milliammeter 24.

A commercial tube which is at present available for use as tube 35 affords for the present application an optimum grid bias range of -10 to -30 volts. The lower negative potential named corresponds to the uncharged condition of the condenser 23, while the higher value corresponds to 20 volts between the terminals of the condenser 23 which voltage affords full scale

deflection of the microammeter 31. The battery 48 provides an initial potential of -10 volts of grid 35^c with respect to the cathode 35^a. With this bias the current through the tube 35^c is approximately 75 milliamperes, this current causing a drop through the resistor 39, which is balanced by the bucking battery 40 so that the recording meter coil 38^c receives no current and the meter registers zero deflection. As the current in the tube 35^c decreases due to increase of its negative grid potential, the voltage of the coil 38^c increases and the instrument is deflected proportional to the decrease of the tube current.

The operation of the instrument will now be explained in connection with the accompanying drawing. For the purpose of explanation it is however assumed that the gears 42, 43 and the shaft 44 are omitted and that the cam 45 is mounted directly on the motor shaft. Also omitted is the second recorder 138 with its accompanying tube and other accessory apparatus. The operation of the system when two or more recorders are employed will be apparent from the description given hereinafter in connection with a single recorder.

To operate the instrument the resistor 4 is adjusted so as to afford a voltage drop of 1 to 5 volts when the switch 1 is closed. The system is adjusted with the switch 1 open, or closed, without carrying load current. After the filaments of the tubes have attained their normal temperature the push button 33 is depressed and the current passing through the tube 26 is adjusted by adjustment of the contact 19^a which under these conditions regulates the potential of the grid 26^c. The adjustment is made so that the bridge is balanced and the instrument 31 reads zero. In other words, the bridge is balanced by regulating the voltage drop across the tube to equal the voltage drop across the resistor 29. Thereafter normally closed contacts of push button 16 are opened by depression of the latter and the current of the tube 17 is adjusted to the desired value by moving the contact 18^a so that a potential is impressed upon the grid 17^d which corresponds to the desired value of current passed by the tube 17 to charge the condenser 23. Thereafter the condenser 23 is adjusted for the desired capacity. It will be observed that the voltage rise of the condenser for a given charging period is inversely proportional to the condenser capacity and directly proportional to the product of charging current and charging time. The condenser is therefore adjusted to such a value that the charging current supplied by the tube 17 will give the desired potential on the grid 26^c in a given time.

If it should be desired to investigate the operation of the contacts 1^b of switch 1 upon closure, for instance, to determine the duration of the arc resulting from the rebound of the switch contact upon closure, the switch 16 is again closed and the motor 41 is started causing rotation of its shaft at a relatively slow speed. The cams 45, 46 and 47 are adjusted so that upon rotation the cam 47 opens the normally closed contacts 25 to permit a current flowing in the tube 17 to pass into the condenser 23 and charge the same. Shortly thereafter the cam 46 closes the contacts 5 thereby connecting the coil 1^a across the bus bars L¹ and L² to energize the switch 1 and effecting closure of the contacts 1^b. If upon closure the contacts 1^b rebound, an arc is created which produces a potential difference at the terminals of the contacts. This renders the tubes 10 and 13 non-conducting by impressing a negative po-

tential on the grids 10^c and 13^c respectively. As a result no current flows through the resistor 22, which reduces the negative potential of the grid 17^c, thereby permitting current to flow in the tube 17 to charge the condenser 23 and lowers the potential of the grid 26^c. The resulting current in tube 26 unbalances the bridge so that the potential of the cathode 26^a changes with respect to the bus bar 8. Upon further rotation of the motor 41 and after the contacts 1^b are at rest in the closed position following the rebound, the tube 17 becomes non-conducting so that the voltage of the condenser 23 does not increase any more and a steady current proportional to the duration of the arcing of switch 1 flows through the tube 26. The cam 45 then closes the contacts 34 to impress upon the grid 35^c and the condenser 36 the potential of the cathode 26^a. This makes the tube 35 less conducting and causes a current flow through the recording instrument 38 which will be indicated thereon. The motor 41 continues to rotate, and after the instrument 38 has made a record, the contacts 34 are again opened. Thereafter the contacts 25 are closed and then the contacts 5 are opened making the instrument available for another operation.

As will be apparent from the foregoing description, the contacts 34 are closed and a record is made by the instrument 38 upon every second operation of the contacts 5 and 25, while, on the other hand, the contacts 34 and 134 are closed during alternate closures of the contacts 5 and 25 as the cam 145 is displaced 180 degrees from the cam 45. As a result, records are made alternately on the instruments 38 and 138 upon successive closures of the contacts 5 and 25.

It will be observed that the condenser 36 is charged and will maintain its charge so as to maintain the deflection of the instrument 38 upon cessation of arcing.

To repeat a measurement on the switch 1 it is only necessary to continue the operation of the motor 41 for another cycle.

The provision of the condenser 36 is of advantage in that it preserves the deflection of the instrument 38 so that it can be read at leisure and if the operation of the switch 1 is repeated the deflection of the instrument 38 on the second and subsequent operations does not have to start from zero, thereby eliminating the result of the inertia of the moving parts of said instrument on its accuracy.

It should further be pointed out that the current which can be handled by the instrument 38 is much higher than the current which could be handled by the instrument 31 and inasmuch as a recording instrument requires for the same accuracy a much higher operating current than an indicating instrument, the arrangement shown affords a graphic record of the phenomena to be investigated. To investigate other phenomena with a different sequence it is only necessary to rearrange the sequences of operation of the switches 25, 34 and 5 by changing the relative adjustment of the cams 47, 45 and 46 on the shaft of the motor 41.

In some cases it may be found advantageous to control the contacts 25, 34 and 134 by cams 47, 45 and 145 respectively, through the medium of relays. Remote control of said contacts will thereby be obtained and extension of sensitive control wires beyond the confines of the instrument will be unnecessary.

We claim:

1. In apparatus for recording the period of

simultaneity of two conditions of a circuit, the combination with a condenser and means responsive to each condition individually and arranged to supply a substantially constant current to said condenser while said conditions persist simultaneously, of a current responsive recording meter, an electron tube arranged to supply current to said recording meter and having a plurality of electrodes including a control electrode adapted to vary the current supplied by said tube in accordance with the voltage difference between said control electrode and another electrode of said tube, a second condenser connected to said control electrode, means for charging said second condenser to a voltage which is proportional to the ultimate voltage of said first condenser, and means for impressing between said control electrode and said other electrode of said tube a voltage which is a function of the voltage of said second condenser.

2. In apparatus for recording individually the duration of each of a plurality of successive transient effects, the combination with means for charging a condenser to a voltage which is proportional to the duration of said effects, of a plurality of current responsive recording meters, one for each effect to be recorded individually, an electron tube for each meter arranged to supply current to the respective meter and each having a plurality of electrodes including a control electrode adapted to vary the current supplied by said tube in accordance with the voltage difference between said control electrode and another electrode of said tube, and selective means for selectively impressing between said control electrode and said other electrode of any one of said tubes a voltage which is a function of the voltage of said condenser.

3. In apparatus for recording individually the duration of each of a plurality of successive transient effects, the combination with means arranged to supply a charge to a condenser which modifies its voltage in proportion to the duration of said effects, of a plurality of current responsive recording meters, one for each effect to be recorded individually, an electron tube for each meter arranged to supply current to the respective meter and having a plurality of electrodes including a control electrode adapted to vary the current supplied by said tube in accordance with the voltage difference between said control electrode and another electrode of said tube, an individual condenser connected to said control electrode, and selective means for selectively impressing upon any one of said last named condensers a voltage which is a function of the voltage of said first named condenser.

4. In apparatus for recording the duration of a transient effect, by providing a voltage which is proportional to the duration of said effect, the combination of a first condenser, a current responsive recording meter, an electron tube arranged to supply current to said recording meter and having a plurality of electrodes including a control electrode adapted to vary the current supplied by said tube in accordance with the voltage difference between said control electrode and another electrode of said tube, a second condenser connected to said control electrode, means for charging said first condenser during the existence of said transient effect, means for charging said second condenser to a voltage which is proportional to the ultimate voltage of said first con-

denser, means for impressing between said control electrode and said other electrode of said tube a voltage which is a function of the voltage of said second condenser, and means for thereafter discharging said first condenser, while maintaining the charge of said second condenser.

5. In apparatus for recording a characteristic of a transient effect, the combination with a condenser and means responsive to a characteristic of a transient and adapted to supply a substantially constant charging current to said condenser while said transient persists, of a current responsive recording meter, an electron tube arranged to supply current to said recording meter and having a plurality of electrodes including a control electrode adapted to vary the current supplied by said tube in accordance with the voltage difference between said control electrode and another electrode of said tube, a second condenser connected to said control electrode, means for charging said second condenser to a voltage which is proportional to the ultimate voltage of said first condenser, means for impressing between said control electrode and said other electrode of said tube a voltage which is a function of the voltage of said second condenser, and means for thereafter discharging said first condenser, while maintaining the charge of said second condenser.

6. In apparatus for measuring the period of simultaneity of two conditions of a circuit, the combination with a condenser, and means responsive to each condition individually and adapted to supply a substantially constant current to said condenser while said conditions persist simultaneously, of a current responsive recording meter, an electron tube arranged to supply current to said recording meter and having a plurality of electrodes including a control electrode adapted to vary the current supplied by said tube in accordance with the voltage difference between said control electrode and another electrode of said tube, a second condenser connected to said control electrode, means for charging said second condenser to a voltage which is proportional to the ultimate voltage of said first condenser, means for impressing between said control electrode and said other electrode of said tube a voltage which is a function of the voltage of said second condenser, and means for thereafter discharging said first condenser, while maintaining the charge of said second condenser.
